COIN CONTROLLED SCALE

Harold L. Walker, Brooklyn, N. Y., assignor to
The Jacobs Bros. Co., Inc., Brooklyn, N. Y.,
a corporation of New York

Application May 17, 1933, Serial No. 671,439

8 Claims. (Cl. 194—47)

This invention relates to a structurally and functionally improved scale.

It is an object of the invention to furnish a mechanism of this character which will be coin or token controlled, and by means of which it will be substantially impossible, upon the depositing of a single token or coin, for more than one person or article to be weighed.

A further object of the invention resides in the provision of an apparatus of this nature which may be subjected to extremes of abuse without the mechanism becoming damaged or substantially worn.

A further object of the invention is that of providing a scale which will embody relatively few parts, each individually simple and rugged in construction and capable of being readily assembled and "set up."

With these and other objects in mind, reference is had to the attached sheets of drawings illustrating practical embodiments of the invention, and in which:

Figure 1 is a sectional side view of a registering and weighing mechanism, constructed in accordance with the teachings of the present invention;

Figure 2 is an enlarged view of certain of the parts as shown in Figure 1;

Figure 3 is a perspective view thereof, and

Figure 4 is a side elevation of a lock actuated mechanism slightly different from that illustrated in the preceding views.

Referring primarily to Figures 1 and 3, it will be noted that the numeral 5 indicates a housing which may be of any desired configuration, and within which—in the embodiment illustrated—an annular band 6 is positioned. This band has on its outer face graduation marks which indicate the weight value of an object placed upon the platform. These graduation marks are visible through an opening 7 in the edge of the casing 5. The band 6 is supported by mounting the same upon a spider 8, which is secured to a shaft 9.

One desirable form of registering mechanism is shown. It is obvious that in lieu of this specific form of mechanism, any desirable arrangement of dial and/or pointer might be employed. In any event, however, it will be necessary to rotate the shaft 9, and with a view to achieving this result, a pinion 10 may be mounted upon the shaft and engage with the teeth of a rack 11 so that as the latter is reciprocated the shaft will rotate.

The weight-receiving mechanism or platform

of the scale has not been shown. Suffice it to say that this may take any desired form and should preferably include a system of levers, depression of which may be resisted by means of a spring 12, or any other suitable mechanism. Also, the weight-receiving mechanism should be connected by means of a rod 13—or otherwise—to a platform or plate 14, which latter, in the embodiment under consideration, has the lower end of the spring 12 attached to it. Thus, when an object is placed upon the weight-receiving support of the scale, the plate 14 will move downwardly, and in view of the fact that the lower end of the rack-bar 11 is supported by this plate, the latter will also tend to move downwardly, thereby rotating the shaft 9.

However, such downward movement of the rack-bar is normally prevented incident to the fact that the shaft carries an annular ratchet 15, the teeth of which are engaged by a pawl 16 or stop 16. The latter may be mounted upon a rockingly supported lever 17, which is counterbalanced as at 18 by a weight. Thus, a lock mechanism is provided, and despite downward movements of the plate 14 the rack-bar will not shift. Consequently, children may jump up and down on the platform or other weight-receiving portion of the scale without affecting movement of the registering mechanism, and likewise, no one will be able to determine the weight value of a person or object disposed upon the platform. In order to release this lock mechanism, a coin or token slot is provided which cooperates with a coin or token receiver to depress the latter by depositing therein or contacting therewith a coin which has been deposited in the slot. None of the foregoing mechanism has been shown, it being well known in the art and being capable of taking many different forms. In any desired manner, however, the depressing of the coin or token receiver serves to correspondingly depress the outer end of a lever 19, the inner end of which is counter-weighted as at 20. This lever is connected by a link 21 to the lever 17, and due to the fact that this link is preferably disposed to extend at a tangent, as well as downwardly, movement on the part of the lever 19 will not alone swing the lever 17 downwardly but will also rock the pawl-carrying end of the same inwardly. This is permitted, due to the fact that the pivot pin which supports the lever 17 is purposely made somewhat loose and the lever is accordingly not confined to rocking movements in a purely vertical plane.

Disposed adjacent the inner end of lever 17 is

is a shaft 22 which is rotatably mounted by the frame work of the scale and is shifted by means of a crank 23 and link 24, which latter is connected to the plate 14. Secured to the shaft 22 is an arcuate member 25, which is provided adjacent its inner edge with a series of spaced tangentially extending stop members 26 and which has an inclined surface 27 extending from the stop members to its outer edge. The inner end of lever 17 terminates in a supporting portion 28 which, when the lever 17 is moved downwardly and inwardly, comes to lie to the rear of the stop portions 26. In such position the pawl 16 is free of the ratchet 15 and the lever 19 may accordingly assume its initial position without the locking mechanism reengaging.

From the foregoing it will be obvious that if a person steps upon the platform of the scale, the plate 14 will be depressed to its proper position, but nothing further will occur. If thereupon, a token or coin is deposited to depress the lever 19, the pawl 16 will shift out of engagement with the teeth of the ratchet 15 and will additionally be supported against reengagement in view of the fact that the contact element 28 of the lever 17 will lie beyond stop elements 26. The rack 11 will now be free to rotate the shaft 9, and accordingly, the lower end of this rack will come to lie upon a spring pressed or other suitable yielding stop member 29 secured to the plate. When arrested by the element 29, the rack will have moved the shaft to a position at which accurate weight indication is given and the parts will remain in this position. However, if the weight upon the platform is decreased to even a minor extent, the arcuate member 25 will rotate counter-clockwise to a sufficient amount to permit the supporting element 28 to move between the tangentially extending stop elements 26. Upon this occurring, the pawl 16 will move into contact with the ratchet 15 and prevent further movements of the registering mechanism, except as they follow incident to a return of such mechanism to normal or zero condition. Obviously, very minor decreases in weight upon the platform would not serve to reengage the locking mechanism, because the arcuate member would be rotated to an insufficient extent to release the lever 17. These decreases would, of course, follow incident to a person shifting around on the platform. However, it has been ascertained that it is virtually impossible for a person to step off a scale platform and another person to step on the scale without causing a decrease of say, for example, five pounds, and irrespective of the weight of the two persons successively occupying the platform. Such a decrease in weight would be sufficient for the supporting element 28 to move between adjacent stop members and thus lock the mechanism.

Obviously the member 25 shifts whether a coin is deposited or not, and so long as weights are placed upon the platform. This is inconsequential, and if in lieu of the crank 23 and link 24, it is preferred to employ a rack and pinion structure, this may readily be achieved, as shown in Figure 4. In this view, the numeral 30 indicates a rack bar which is secured to the plate 14, the teeth of which mesh with a pinion 31. An annular member 32, corresponding in cross section to that of the member 25 is mounted upon the shaft 33, which supports the member 32 and the pinion 31. Under these circumstances the lever 17 will cooperate with the member 32 in exactly the same

manner as that heretofore described in connection with the arcuate element 25.

Obviously, numerous changes of structure and rearrangements of the parts may be resorted to without departing from the spirit of the invention as defined by the claims.

Having described my invention, what I claim as new and desire to secure by Letters Patent is:

1. A scale including, in combination, a registering mechanism, a rotatable shaft forming a part of said mechanism, a member shiftably responsive to a weight associated with said scale, means whereby said shaft may rotate responsive to the degree of movement of said member, an annular ratchet secured to said shaft, a pawl engaging said ratchet, a lever mounting said pawl, means for supporting said lever in a position wherein said pawl is disengaged from said ratchet, a coin releasing mechanism for shifting said lever, said supporting means comprising a body connected to and shiftable in response to movements of said member, and a series of lever diverting elements associated with said body and acting to move the same to an unsupported position in response to movements of said member. 25

2. A scale including, in combination, a registering mechanism, a rotatable shaft forming a part of said mechanism, a member shiftably responsive to a weight associated with said scale, means whereby said shaft may rotate responsive to the degree of movement of said member, an annular ratchet secured to said shaft, a pawl engaging said ratchet, a lever mounting said pawl, means supporting said lever in a position wherein said pawl is disengaged from said ratchet, a coin releasing mechanism for shifting said lever, said supporting means comprising a rotatable body having a plurality of lever diverting surfaces adjacent its inner edge, means for connecting said body to rock in response to movements of said member and means forming a part 35 of said lever and cooperating with said diverting means whereby to shift said lever to unsupported condition in response to movements of said member. 45

3. A scale including a registering mechanism, a rotatable shaft forming a part of said mechanism, an annular ratchet secured to said shaft, a pawl engaging said ratchet, a lever mounting said pawl, a supporting member disposed adjacent said lever and to support the same in a position where said pawl clears said ratchet, and an angularly extending link connected to said lever whereby upon said link being moved, said lever will be rocked to have said pawl clear said ratchet 55 and to have its end swung to engage said supporting member.

4. A scale including, in combination, a member movable responsive to loads imposed upon said scale, a registering mechanism to evaluate said loads, means normally locking said registering mechanism against operation and including a lever shiftable to a position to permit of said registering mechanism operating, means for so shifting said lever, means for maintaining said lever in shifted condition, said latter means including a surface to be operatively engaged by said lever, means adjacent said surface and movable in one direction to divert said lever to its locking position, and means coupling said diverting means to 70 said load responsive member whereby upon the latter moving in a certain direction, said diverting means will act to shift said lever to cause said registering mechanism to be locked against operation. 75

5. A scale including, in combination, a member movable responsive to loads imposed upon said scale, a registering mechanism to evaluate said loads, means normally locking said registering mechanism against operation and including a lever shiftable to a position to permit of said registering mechanism operating, means for so shifting said lever, an annular member operatively coupled to said load responsive member and presenting a surface to be engaged by said lever to support the same in shifted condition, and tangentially extending stop elements mounted by said annular member and to engage said lever to divert the same from supported condition upon said annular member being rotated in one direction, the diversion of such lever resulting in the latter cooperating with said registering mechanism to lock the same against operation. 10 15
6. A scale including, in combination, a member movable responsive to loads imposed upon said scale, a registering mechanism to evaluate said loads, means normally locking said registering mechanism against operation and including a lever shiftable to a position to permit of said registering mechanism operating, means for so shifting said lever, an arcuate member presenting a lever supporting surface to retain said lever in shifted position, means for coupling said said latter member to said load responsive member whereby both will have simultaneous movement, and stop elements associated with said arcuate member and cooperating with the lever when the former is moved in a certain direction to divert said lever out of operative engagement with said supporting surface, the diversion of such lever resulting in the latter cooperating with said registering mechanism to lock the same against operation. 20 25 30 35
7. A scale including, in combination, a member movable responsive to loads imposed upon said scale, a registering mechanism to evaluate said loads, means normally locking said registering mechanism against operation and including a lever shiftable to a position to permit of said registering mechanism operating, means for so shifting said lever, a member mounted for oscillation and connected to said weight responsive member, said oscillating member presenting a lever supporting surface with which said lever is to be shifted into engagement, and stop members disposed adjacent said surface and cooperating with said lever to divert the latter therefrom upon said oscillating member being rocked in one direction, the diversion of such lever resulting in the latter cooperating with said registering mechanism to lock the same against operation. 10 15 20 25 30 35
8. A scale including, in combination, a member movable responsive to loads imposed upon said scale, a registering mechanism to evaluate said loads, means normally locking said registering mechanism against operation and including a lever shiftable to a position to permit of said registering mechanism operating, means for so shifting said lever, a member mounted for oscillation and connected to said weight responsive member, said oscillating member presenting a lever supporting surface with which said lever is to be shifted into engagement, and stop members disposed adjacent said surface and cooperating with said lever to divert the latter therefrom upon said oscillating member being rocked in one direction, the diversion of such lever resulting in the latter cooperating with said registering mechanism to lock the same against operation. 10 15 20 25 30 35
